UNITED STATES PATENT OFFICE.

JAMES F. CASEY, OF NEW YORK, N. Y.

MOVING DAYLIGHT SIGN.

Application filed March 5, 1929. Serial No. 344,409.

This invention relates generally to signs and has more particular reference to a novel moving daylight sign.

The invention has for an object the provision of a device of the class mentioned which is of simple durable construction, desirable in use and efficient in action, and which can be manufactured and sold at a reasonable cost.

The invention proposes the use of a casing provided with an open top and an open front side and arranged for supporting a mirror at an inclination between the said top and side, and a sign stencil of flexible material arranged for moving around the said mirror and supported upon rollers, certain of which are rotated by an electric motor for causing the sign to move. Light passing thru the open top passes thru a portion of the flexible sign stencil and strikes the inclined mirror and thereafter is reflected outwards thru the open front and when seen by by-passers presents a moving sign. A brush is supported within the lower portion of the casing and arranged for automatically dusting the said sign stencil so as to keep it free from dust and clear for the passage of light.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

Fig. 1 is a plan view of a device constructed according to this invention.

Fig. 2 is a front elevational view thereof.

Fig. 3 is a vertical transverse sectional view taken on the line 3—3 of Fig. 2.

Fig. 4 is a fragmentary elevational view of the left hand portion of the device as seen in Fig. 2 with the front left door thereof open.

Fig. 5 is a fragmentary front elevational view of the right hand portion of the device as seen in Fig. 2 with the front right door open.

Fig. 6 is a fragmentary front elevational view of a portion of the device as shown in Fig. 2 with the bottom central door open.

Fig. 7 is a detail view of the brush actuating mechanism.

Fig. 8 is a view similar to a combined view of Figs. 4 and 5, but disclosing a modified form of the device.

The reference numeral 10 indicates gen-

erally a casing provided with a top side 11 and a bottom side 12, front side 13 and a rear side 14. The top side 11 has a central opening 15 bounded by longitudinal front and rear sides 16 and 17, respectively.

The front side 13 of the casing is provided with a central opening 18 bounded by longitudinal top and bottom sides 19 and 20, respectively. A front left door 21 is pivotally mounted at its outer edge on one of the edges of the casing and is provided with a manipulating knob 22. A front right hand door 23 is pivotally mounted along its outer edge on the right end of the casing 10, and is provided with a manipulating knob 24. A bottom central door 25 is pivotally mounted along its bottom edge on to the bottom edge of the casing and is provided with a manipulating knob 26.

The rear side 14 of the casing has top and bottom longitudinal portions 27 and 28, respectively and an inclined angular central portion 29. A mirror 30 is secured upon the front side of the inclined portion 29 and is adapted for reflecting light passing thru the top opening 15, reflecting said light thru the front opening 18.

The top longitudinal sides 16 and 17 are provided with spaced grooves 31 on their inner sides and spaced glasses 32 engaged in these grooves. A continuous flexible sign stencil 33 passes between the spaced glasses 32 and extends over rollers 34 supported upon standards 35 and 36 projecting from portions of the casing 10. The rollers 34 on the left hand portion of the device are fixed upon shafts 37 which support sprocket wheels 38 and a sprocket chain 39 engages over these sprocket wheels and over a sprocket wheel 40 fixed on the shaft of an electric motor 41 secured within the casing 10. End plates 42 are arranged transversely at the ends of the inclined mirror 30.

A stencil sign cleaning brush 43 is mounted on one end of bell crank 44 which is pivotally mounted intermediate of its ends as at 45 upon the casing 10 and a link 46 pivotally connects with the free end of the bell crank and with a rack 47 slidably mounted in the casing 10 and engageable with the teeth of a gear 48 having certain of its teeth stripped. A shaft 49 supports the gear 48 and also a ratchet wheel 50 engaged by a pawl 51 arranged to hold the ratchet wheel against rotation in one direction. The hook 52 projects from the stencil sign element 33 and each time

this hook passes the ratchet wheel 50 it engages in one of the teeth of the ratchet wheel and advances it one tooth.

In operation of the device the electric motor 41 is energized for rotating certain of the rollers 34. These rollers act as driver rollers and cause the stencil sign element 33 to move in a continuous path around all of the rollers 34, the other of the said rollers coacting as idlers. Light passes thru top opening 15 of the casing, passes thru the spaced glasses 32, the sign element 33 and strikes and is reflected from the mirror 30 thru the front opening 18. Persons viewing the sign will see a moving sign with characters as determined by those on the stencil sign element 33.

Each time the stencil sign element makes one complete revolution, hook 52 engages a tooth of the ratchet 50 for turning the ratchet one tooth, the pawl 51 preventing back turning and the teeth of gear 48 moves the rack 47 forwards against action of a spring 53 coacting between rack 47 and a standard 54 secured on the casing 10. Forward motion of the rack 47 is transmitted by the link and bell crank for urging the brush 43 against the outer side of the sign element 33. When the stripped portion of the gear 48 reaches the rack, the rack is released and is drawn rearwards by the spring 53 for causing the brush 43 to disengage from the sign element, for periodically cleaning the same from dust and dirt only when in engaged position.

It is to be understood that stencil 33 may be changed so as to feature any suitable advertising words or illustrations.

In the modified form of the device illustrated in Fig. 8 the standards 35 and 36 are shown supporting a plurality of rollers 34^a and 34'. The rollers 34^a are idler rollers and the rollers 34' are fixed on the shaft 37. The flexible stencil sign element 33 is wound back and forth between all of the said rollers in a continuous fashion as illustrated on the drawing for materially lengthening the operative length of the side element. In other respects this form of device is similar to the preferred form previously described.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In a daylight moving sign, a casing with a top side having a central opening bounded by longitudinal sides formed with spaced grooves on their inner sides for supporting spaced glasses to guide a flexible stencil sign element, and standards projecting from the interior of the casing for supporting guide rollers to guide the said flexible stencil sign element between the spaced glasses. 60 65

2. In a daylight moving sign, a casing with a top side having a central opening bounded by longitudinal sides formed with spaced grooves on their inner sides for supporting spaced glasses to guide a flexible stencil sign element, and standards projecting from the interior of the casing for supporting guide rollers to guide the said flexible stencil sign element between the spaced glasses, doors being mounted on the casing for normally covering the said standards. 70 75

3. In a daylight moving sign, a casing with a top side having a central opening bounded by longitudinal sides formed with spaced grooves on their inner sides for supporting spaced glasses to guide a flexible stencil sign element, and standards projecting from the interior of the casing for supporting guide rollers to guide the said flexible stencil sign element between the spaced glasses, doors being mounted on the casing for normally covering the said standards, and means for brushing and cleaning the said stencil sign element being mounted within the casing. 80 85 90

4. In a daylight moving sign, a casing with a top side having a central opening bounded by longitudinal sides formed with spaced grooves on their inner sides for supporting spaced glasses to guide a flexible stencil sign element, and standards projecting from the interior of the casing for supporting guide rollers to guide the said flexible stencil sign element between the spaced glasses, doors being mounted on the casing for normally covering the said standards, and means for brushing and cleaning the said stencil sign element being mounted within the casing, said means being arranged to function automatically and periodically. 95 100 105

In testimony whereof I have affixed my signature.

JAMES F. CASEY.
